UNITED STATES PATENT OFFICE

ROY A. WILEY AND CHESLEY L. WOLFE, OF SOUTH BEND, INDIANA, ASSIGNORS TO THE ELECTRIC SPRAYIT COMPANY, OF SOUTH BEND, INDIANA, A CORPORATION OF DELAWARE

BLOW TORCH

Application filed March 7, 1929. Serial No. 345,028.

This invention has to do with liquid fuel burners, and is particularly concerned with an improved burner of novel construction, arrangement and operation which may be 5 made up as a blow torch, or as a blow torch attachment for use with a paint-spraying device, or as a laboratory heater, or as a cooking stove. The foregoing are but a few of the many obvious adaptations of the invention.

There are a number of difficulties and objections attendant upon the operation of the ordinary blow torch. It burns only a highly volatile fuel such as gasoline, requires 15 pre-heating of the nozzle before using, depends on vaporization of the fuel, necessitates frequent pumping to maintain sufficient air pressure on the fuel, is rather dangerous to handle, requires the attention of 20 a skilled operator, and is expensive to manufacture.

One of the objects of the invention is to provide an improved blow torch of novel construction, arrangement and operation.

The blow torch of the invention is 25 designed for operation with low grade fuel oils, or kerosene, or more volatile liquids such as gasoline, benzine or alcohol. It will burn kerosene, for instance, as well or better than the ordinary torch will burn gasoline; it produces an intensely hot blast; it does not require any pre-heating at all; it can be started instantly by holding a lighted match below the front end of the nozzle; it 30 will not drip fuel when being started; it is absolutely safe; it operates at a constant, non-fluctuating air pressure; it costs but little to manufacture; it can be operated with ease by a person having no previous experience; and it can be made up not only in the form of a typical blow torch, but as a stand heater, or as an attachment for application to and use with a portable paint-spraying device, whereby such device may be converted 40 in a few moments into an efficiently operating blow torch.

While the foregoing statements are indicative in a general way of the nature of the invention, other objects, advantages and 45 adaptations will be apparent to those skilled

in the art upon a full understanding of the improved blow torch.

Several different adaptations of the invention are presented herein for the purpose of exemplification, but it will of course be appreciated that the invention is susceptible of embodiment in various other structurally modified forms coming equally within the scope of the appended claims.

In the accompanying drawings:

Fig. 1 is a partially sectioned side view of a blow torch embodying the invention;

Fig. 2 is a partially sectioned side view of a stand heater embodying the invention;

Fig. 3 is a side view of a hand portable paint-spraying device equipped with a blow torch attachment embodying the invention;

Fig. 4 is a sectional view, illustrating in detail the attachment shown in Fig. 3;

Fig. 5 is a perspective view of a cooking stove, the individual burners of which embody the invention;

Fig. 6 is a section through one of the stove burners shown in Fig. 5; and

Fig. 7 is a fragmentary sectional view 75 through a novel form of needle valve which may be used in connection with any of the forms of burners shown.

The blow torch shown in Fig. 1 includes a container 10 in which a quantity of liquid fuel is adapted to be placed. The container is preferably flared about its bottom to provide a stable support when set upon a horizontal surface, and is equipped at one side with a handle 11 by which the device may be conveniently held. A tubular member 12 screws into the top of the container and terminates at its upper end in a horizontally extending head 13. The head is exteriorly threaded at its front end and is provided within such end with a chamber 14. A nozzle 15 is screwed onto the front end of the head and contains in its rear face a conical recess 16 which forms the front portion of the chamber 14.

The air used in operating the torch is fed under pressure from a suitable compressor or storage tank (not shown) through a long flexible hose 17, which hose connects with a passageway 18 in the head opening into the

chamber 14. The passageway 18 also communicates with the interior of the container 10 above the level of the fuel through a small duct 19.

- 5 The fuel used in operating the torch is caused by the pressure of the air on the top of the same to flow upwardly in a tube 20 into a small bore 21 in the head, from which bore it flows forwardly into a tube 22 which projects from the bore 21 into the chamber 14. 10 The front end of the tube 22 tapers to a small opening 23, and a needle valve 24 which controls the flow of fuel through the opening 23 is positioned centrally within the tube 22. 15 The stem 25 of the needle valve extends rearwardly through the bore 21 and is screwed into a bushing 26 which is mounted in the rear end of the bore. A knurled handle 27 is secured to the valve stem 25 exteriorly of the head, and, to diminish or increase the flow of fuel from the front end of the tube 22, it is merely necessary to turn the handle 27 in one direction or the other.

The nozzle 15 is provided in its front end 20 with an elongated cylindrical bore 28 which communicates centrally with the chamber 14 through a small orifice 29 which is located in front of and closely adjacent to the opening 23 in the tube 22. The inner wall 30 of the nozzle is separated from the outer wall 31 by an annular chamber 32 which communicates with the bore 28 through two sets of apertures 33 and 34 positioned respectively adjacent the front and rear ends of the chamber 32. A plate 35 is positioned crosswise of the bore 28 between the front and rear apertures 33 and 34, a short distance in front of the orifice 29, and is provided with a large number of minute uniformly distributed perforations 36 through which the combustible mixture is forced. The plate 35 is seated against a narrow annular shoulder 37 in the bore 28, and is held against such shoulder by a readily removable split spring ring 38 which is seated in a shallow annular groove in the bore just in advance of the plate.

When the blow torch is to be started, the compressor is turned on and air under pressure is caused to flow rapidly into the chamber 14 and out through the orifice 29 into the bore 28 of the nozzle. The needle valve 24 is then cracked a little, whereupon the pressure of the air in the top of the container 10 forces the fuel up through the tube 20 and out of the front end of the tube 22 into the front portion of the chamber 14, where such fuel mixes with the rapidly moving blast of air passing about the front end of the tube 22 through the orifice 29, is further broken up by the perforated diaphragm 35 and is blown with the air from the front end of the bore 28, in the form of a fine vapor. Such vapor will ignite very easily, and it is only necessary to hold a lighted match mo-

mentarily just below the front end of the nozzle in order to place the blow torch in full operation.

When the blow torch is being started, any of the fuel which is not completely vaporized when it reaches the perforated diaphragm 35 will be pocketed in the rear portion of the bore 28 behind the diaphragm and will drain down into the chamber 32 through the openings 34. As the blow torch gets into full operation, the nozzle heats up, and any fuel which has drained down into the chamber 32 in the nozzle is quickly vaporized by the heat transmitted thereto and passes back through the openings 34 into the bore 28, where it joins the combustible mixture passing through the bore and is consumed with such mixture at the front end of the nozzle. The openings 33 allow outside air to flow into the chamber 32. Should any of the fuel which is being discharged from the front end of the tube 22 into the air stream in the front portion of the chamber 14, fail to pass through the orifice 29 when the blow torch is first being started, it will drain into a well 39 in the passageway 18 and return from there into the container through the duct 19.

In order to shut off the blow torch, it is merely necessary to close the needle valve. The richness of the mixture being burned may be easily varied by changing the position of the needle valve.

The head and nozzle construction shown in Fig. 1 may be incorporated also in a stand burner, as shown in Fig. 2. In that view, the head 40 on which the nozzle 41 is mounted is arranged with the jet tube 42 in a vertical position, and the stem 43 of the needle valve 44 which controls the opening 45 in the upper end of the jet tube extends downwardly through a sleeve 46. The sleeve 46 has a fluid-tight connection at its lower end with the bottom of the container 47, and the stem 43 of the needle valve is in screw-threaded engagement with the container and terminates below the same in a knurled handle 48. The container is preferably supported in a slightly elevated position on an openwork base 49, which base renders the handle 48 easily accessible for adjustment of the burner. A skeleton work support 50 of any suitable description is preferably carried by the burner in a position above the upper end of the nozzle.

In Figs. 3 and 4 is shown a slightly modified nozzle construction which may be applied easily to, and used advantageously with, a paint-spraying gun. As in the previously described forms, the nozzle is provided with a long, substantially cylindrical bore 51, inner and outer walls 52 and 53 which are spaced to form therebetween a chamber 54, a finely perforated plate or screen 55 posi-

tioned crosswise of the bore 51 a short distance in front of the hole 56 in the partition 57 which separates the bore 51 from the chamber 58 where the streams of fuel and air are 5 brought together, and front and rear sets of openings 59 and 60 connecting the chamber 54 with the bore 51 forwardly and rearwardly of the diaphragm 55. The partition 57, instead of being formed as a part of the 10 inner wall 52 of the nozzle, constitutes the front portion of an adapter sleeve 61 over which the rear end of the nozzle proper is screwed. The adapter sleeve is screwed into the front end of the barrel 62 of a paint-spraying gun 63, in which barrel a jet tube 64 is centrally positioned.

The air used in operating the torch is fed through a flexible hose 65 to the chamber 58 formed in the barrel behind the adapter 20 sleeve. The fuel used in operating the torch is caused by the pressure of the air on the top of the same in the paint container to flow upwardly through a tube 66 into the jet tube 64, from which it is discharged through an 25 opening 67 into the stream of air passing through the chamber 58 into the orifice 56. The flow of air through the chamber 58 may be controlled by manipulating a trigger-like 30 finger piece 68, and the character of the flame produced may be varied by screwing the nozzle proper forwardly or rearwardly with respect to the adapter sleeve, a knurled rim 69 being provided on the rear end of the nozzle for that purpose. The density or 35 richness of the air and vapor mixture projected through the orifice 56 may be regulated by turning the adapter sleeve whereby to move the orifice toward or away from the opening 67 in the jet tube. The outer sides 40 of the front end of the jet tube 64 may advantageously be provided with angularly extending channels 70 which will impart a whirling motion to the rapidly moving air stream. This feature may also be incorporated, if desired, in the forms shown in 45 Figs. 1 and 2.

In Figs. 5 and 6 is shown an adaptation of the invention to an ordinary cooking stove. Each one of the stove burners is substantially 50 the same in construction, arrangement and operation as the burner shown in Fig. 2.

The fuel jet tubes 71 are all connected with a common fuel supply pipe 72 by branch 55 pipes 73, and valves 74 having conveniently accessible operating handles 75 are mounted in the pipes 73 at the junctions with the pipe 72 for controlling the flow of fuel through the openings 76 in the upper ends of the 60 tubes 71. The conical air chambers 77 surrounding the upper ends of the tubes 71 are connected with a compressed air supply pipe 78 by branch pipes 79, and valves 80 having operating handles 81 are located in the pipes 65 79 for controlling the flow of air about the

upper ends of the tubes 71 and through the orifices 82.

The air supply pipe 78 connects with an air compressor, or other source of compressed air, and is provided with a shut-off valve 83. 70 A branch pipe 84 extends from the pipe 78 into the upper portion of a closed fuel tank 85, whereby to place pressure upon the top of the fuel in such tank. The fuel pipe 72 extends into the upper portion of the tank 75 85 and terminates in an open end near the bottom of the tank.

The openings in the stove above the burners are spanned by openwork grids 86 which are adapted to support cooking utensils in 80 properly spaced relation to the upper ends of the burners, and the central portions 87 of the grids are preferably of upwardly diverging conical form in order to spread the 85 flames.

When the stove is not in use, all of the valves, including the valve 83, are closed. When it is desired to operate one of the burners, the valve 83 is opened, and the valves 74 and 80 associated with the particular burner 90 to be used are opened. A lighted match is then placed at the edge of the air and fuel mixture rising through the grid and the fuel valve 74 is progressively opened until the air and fuel mixture is sufficiently rich to support 95 combustion.

In Fig. 7 is shown a modified form of needle valve which may be used in conjunction with any of the various burner adaptations shown. The stem of the valve is normally maintained in an axially elongated condition by means of a spring 88 which is interposed between two portions 89 and 90 of the stem. The extent to which the stem portions can be separated by the spring may be limited by any suitable means, such as a head 91 on one of the portions which engage within a socket 92 in the other. The spring 88 permits the stem portion 89 carrying the tip of the valve to yield resiliently toward the stem portion 90, with the result that contraction or expansion of the valve seat 93 due to temperature changes will not affect proper seating of the valve, as the action of the spring will automatically compensate for 105 such changes.

We claim:

1. In a blow torch, a tube having a single constricted opening in the rear end thereof through which air and fuel are blown and one or more openings in the side thereof adjacent the front end, a casing surrounding said tube and communicating with the interior thereof through said openings and a perforated diaphragm positioned crosswise of the tube rearwardly of the side openings. 120
2. In a blow torch for operation with a liquid fuel, an inner tube having a single constricted opening in the rear end thereof through which air and fuel are blown and 125
3. In a blow torch, a tube having a single constricted opening in the rear end thereof through which air and fuel are blown and 130

openings in the side thereof adjacent the front and rear ends, a casing surrounding the tube and communicating therewith and a perforated diaphragm positioned crosswise of the tube between the front and rear side openings.

3. In a blow torch for operation with a liquid fuel, an inner tube having a constricted opening in the rear end thereof through 10 which air and fuel are blown and one or more openings in the side thereof, a perforated diaphragm positioned crosswise of the tube, and an outer tube positioned about the inner tube in spaced relation thereto at the 15 location of the side openings to form a communicating chamber.

4. In a blow torch for operation with a liquid fuel, an inner tube having a constricted opening in the rear end thereof through 20 which air and fuel are blown and openings in the side thereof adjacent the front and rear ends, a perforated diaphragm positioned crosswise of the tube between the front and rear side openings, and an outer tube positioned about the inner tube in spaced relation thereto at the locations of the side openings to form a communicating chamber.

5. In a blow torch for operating with liquid fuel, a nozzle comprising an elongated 30 tubular member having a relatively wide tubular bore open at the front end to the atmosphere, a closure wall enclosing the rear end of said tubular member, said closure wall having a restricted nozzle opening, means for forcing an atomized fuel stream and air sufficient for complete combustion of the fuel through said nozzle opening into said bore, said tubular member having on its under side a chamber communicating with said bore 35 on the front side of said nozzle opening for withdrawing liquid fuel collecting in front of the nozzle opening from the stream and returning it to the stream in vaporized form when heated.

45 6. In a blow torch for operating with liquid fuel, a nozzle comprising an elongated tubular member having a relatively wide tubular bore open at the front end to the atmosphere, a closure wall enclosing the rear end of said 50 tubular member, said closure wall having a restricted nozzle opening, means for forcing an atomized fuel stream and air sufficient for complete combustion of the fuel through said nozzle opening into said bore, said tubular member having on its under side a chamber 55 communicating with said bore on the front side of said nozzle opening for withdrawing liquid fuel collecting in front of the nozzle opening from the stream and returning it to the stream in vaporized form when heated, and a perforated baffle positioned cross-wise 60 of the nozzle bore between the front and rear ends of the same.

65 7. In a blow torch for operating with liquid fuel, a nozzle in the form of an elongated

member having a relatively wide tubular bore open at the front end to the atmosphere and a closure wall enclosing the rear end, a restricted nozzle opening in said rear wall, said opening being outwardly tapered at the rear end and constituting a compressed air admission duct, and a fuel supply pipe having an outlet nozzle opening into said outwardly tapered nozzle opening on the rear side of said rear wall.

8. In a hand-portable blow torch for operation with liquid fuel, the combination of a torch unit comprising an air duct having a restricted nozzle opening at the front end, a fuel supply tube extending through said duct and having an outlet nozzle adjacent said nozzle opening and to the rear thereof, a fuel container connected to said fuel tube, a source of compressed air connected to said duct and to said container for supplying said fuel to said nozzle opening and producing a stream of atomized fuel mixed with air sufficient for complete combustion thereof issuing in front of said nozzle opening, and a tubular stream guide extending in front of said nozzle opening around the stream to hold the flame at a distance from the nozzle opening, said tubular guide being open at the front end and having a perforated baffle between said front end and the nozzle opening.

9. In a hand-portable blow torch for operation with liquid fuel, the combination of a torch unit comprising an air duct having a restricted nozzle opening at the front end, a fuel supply tube extending through said duct and having an outlet nozzle adjacent said nozzle opening and to the rear, thereof, a fuel container connected to said fuel tube, a source of compressed air connected to said duct and to said container for supplying said fuel to said nozzle opening and producing a stream of atomized fuel mixed with air sufficient for complete combustion thereof issuing in front of said nozzle opening, and a tubular stream guide extending in front of said nozzle opening around the stream to hold the flame at a distance from the nozzle opening, said tubular guide having a compartment segregated from the stream space but communicating therewith to withdraw from the space in front of said nozzle opening accumulation of liquid fuel and return it to the stream in vaporized form when heated.

10. In a hand-portable blow torch for operation with liquid fuel, the combination of a torch unit comprising an air duct having a restricted nozzle opening at the front end, a fuel supply tube extending through said duct and having an outlet nozzle adjacent said nozzle opening and to the rear thereof, a fuel container connected to said fuel tube, a source of compressed air connected to said duct and to said container for supplying said fuel to said nozzle opening and producing a stream of atomized fuel

- mixed with air sufficient for complete combustion thereof issuing in front of said nozzle opening, a tubular stream guide extending in front of said nozzle opening around the stream to hold the flame at a distance from the nozzle opening, said tubular guide having a compartment segregated from the stream space but communicating therewith to withdraw from the space in front of said nozzle opening accumulation of liquid fuel and return it to the stream in vaporized form when heated, and a perforated baffle across said tubular guide between its front end and said nozzle opening.
- 15 11. In a blow torch for operating with liquid fuel, a nozzle comprising an elongated tubular member having a relatively wide tubular bore open at the front end to the atmosphere, a closure wall enclosing the 20 rear end of said tubular members, said closure wall having a restricted nozzle opening, means for forcing an atomized fuel stream and air sufficient for complete combustion of the fuel through said 25 nozzle opening into said bore, said tubular member having on its under side a chamber communicating with said bore on the front side of said nozzle opening for withdrawing liquid fuel collecting in front of the nozzle.
- 30 In witness whereof we have hereunto subscribed our names.
